PREPARATION OF CARBONYLS OF GROUP
VIb METALS

John H. Wotiz, Mentor, Ohio, assignor to Diamond Alkali Company, Cleveland, Ohio, a corporation of Delaware
No Drawing. Filed Jan. 28, 1960, Ser. No. 5,103
17 Claims. (Cl. 23—203)

This invention relates to a new and improved process of preparing a carbonyl of a group VIb metal.

Group VIb metals as referred to in the specification and claims are tungsten, molybdenum and chromium. In contrast to materials such as cobalt or iron carbonyls, chromium hexacarbonyl up to this time has generally been difficult to prepare. For example, while chromium hexacarbonyl has previously been prepared by the reaction of chromium chloride with phenyl magnesium bromide in the presence of carbon monoxide, the yields often have been undesirably low, e.g., as in the preparation reported in the text "Inorganic Syntheses" by E. Mc-Crary (1950) page 156. On the other hand, the carbonyls of tungsten and molybdenum have heretofore been prepared via the use of metallic reducing agents, e.g., zinc.

The present invention comprises a new and improved method of preparing hexacarbonyls of group VIb metals, e.g., chromium hexacarbonyl, by reacting together, preferably in the presence of hydrogen, at a superatmospheric pressure and at an elevated temperature, carbon monoxide, a source of a group VIb metal, e.g., in the case of chromium either a chromium compound or metallic chromium, iodine or an iodine-containing compound, whether added as such or generated in situ, and a nitrile such as acetonitrile (CH_3CN). By carrying out the reaction in a nitrile the use of a reducing metal such as zinc or magnesium as heretofore considered essential and certain difficulties characterizing prior processes for preparing hexacarbonyls of group VIb metals are avoided in the absence of any reducing metal.

The term "nitrile" as used in the specification and claims is intended to refer to compounds of the formula $\text{R}(\text{CN})_n$ wherein n is 1 or 2; R is an alkyl group such as methyl, ethyl, propyl, butyl, or the like; aryl such as phenyl, or in the case where n is 2, an alkylene radical such as ethylene, propylene, butylene or the like. Examples of suitable nitriles of this type are acetonitrile, which is preferred at present, butyronitrile, benzonitrile, propionitrile, succinonitrile, and the like.

The practice of this invention may be illustrated by the following equation:

wherein M is a group VIb metal.

In carrying out the present process, there are combined in a pressure-resistant reaction vessel, such as an autoclave, provided with an agitator and temperature control means, a mixture of a source of a group VIb metal, e.g., a trivalent chromium compound such as a chromium halide compound selected from the group consisting of chromium iodide, chromium chloride and chromium bromide, preferably chromic trichloride, a chromium oxide, e.g., Cr_2O_3 ; a divalent chromium compound such as chromous iodide; tungsten hexachloride, molybdenum pentachloride or the like; or chromium, molybdenum or tungsten metals as such. The chromium or other group VIb metal may be employed in the form of an ore, e.g., chromite (FeCr_2O_4) or other chromium ores.

Iodine is added when the mixture does not also include chromium or other group VIb metal iodide. The iodine

2

may otherwise be introduced as free iodine, iodine monochloride, ethylene diiodide, alkali metal iodides, i.e., iodides of lithium, sodium, potassium or the like, or alkaline earth metal iodides, i.e., iodides of calcium, barium, strontium, or the like, magnesium iodide, aluminum iodide, zinc iodide, or the like, and the nitrile, e.g., acetonitrile, present in an amount sufficient to dissolve and/or suspend the reactants, using a neutral inert solvent such as hexane or benzene.

These reactants are combined with carbon monoxide and, preferably hydrogen, typically added at intervals to maintain a desired pressure, the ensuing reaction being conducted at a superatmospheric reaction pressure resulting from an initial total pressure of 1000 to 10,000 p.s.i.g. at 30° C.; in certain instances an initial pressure as low as 500 p.s.i.g. may be employed.

The reaction temperature should be maintained within the range from about 150° to 325° C. Preferably, the temperature is of the order of 200° C., e.g., 180° to 240° C. Temperatures below about 150° C. generally result in undesirably low yields.

The amount of nitrile to be employed is dictated by the amount of reactants employed, it generally being desired that at least 3 mols of the nitrile to each mol of metal compound be used, e.g., 1 mol CrCl_3 to 3 mols acetonitrile.

Generally, the amount of hydrogen introduced, when employed, is regulated by introducing sufficient hydrogen to increase the pressure within the reactor preferably about 2000 p.s.i.g. @ 200° C., in addition to the pressure of carbon monoxide, the over-all gas pressure being controlled to be above 8000 p.s.i.g. @ 200° C., and preferably about 8000–12,000 p.s.i.g. @ 200° C., a specifically preferred total reaction pressure being about 10,000 p.s.i.g. @ 200° C. The weight ratio of carbon monoxide to hydrogen may vary from about 1:0 to 1:1. The carbon monoxide and hydrogen may be added as such or in the form of a mixture such as exists in water gas or synthesis gas.

When reaction is complete, which is generally evidenced by a drop in the reactor pressure corresponding to the utilization of carbon monoxide during the reaction, e.g., a 3000 p.s.i.g. pressure drop being typical, the carbonyl product can be separated in any suitable way, as by steam distillation or sublimation. The hexacarbonyl product such as chromium hexacarbonyl is useful as an intermediate or as a starting material in the preparation of various chromium compounds including different chrome organic compounds. In addition, the chromium carbonyl advantageously can be used to plate chromium metal onto metal surfaces by thermal decomposition of the carbonyl.

The proportions of the reactants may be varied somewhat. However, it is generally desired to employ at least substantially stoichiometric proportions of carbon monoxide and the group VIb compound, i.e., chromium compound, preferably chromium chloride, i.e., at least about 6 mols CO/mol of the group VIb metal compound. It is preferred to use an excess of carbon monoxide. A sufficient quantity of iodine, e.g., at least 1 mol of I_2 /mol of CrCl_3 , preferably 3:2, whether added as such or generated in situ, is used to effect the desired reaction. The minimum amount of iodine generally is about 0.1 mol I_2 to 1 mol of the group VIb metal. In the case of tungsten or molybdenum the iodine can be omitted if desired as can the hydrogen. The carbon monoxide is introduced by providing a carbon monoxide atmosphere in the reaction chamber.

While the exact mechanism of the reactions involved is not completely understood, it is believed that the fol-

Following reactions occur in the case of the preparation of $\text{Cr}(\text{CO})_6$:

As the foregoing equations indicate, iodine or an iodide converts CrCl_3 to CrI_3 (or CrI_2) which then dissociates to Cr^0 and I_2 .

In order that those skilled in the art may more completely understand the present invention and the preferred methods by which the same may be carried into effect, the following specific examples are offered.

EXAMPLE 1

Preparation of chromium hexacarbonyl:

A two-liter stirred autoclave is charged with 300 ml. of CH_3CN , 32 g. (0.2 mol) of CrCl_3 , 76 g. (0.3 mol) of powdered I_2 , and an additional 200 ml. CH_3CN , to wash down all solid reactants from the sides of the reactor. The vessel is then sealed and purged three times with short blasts of CO. The vessel is then charged to 5400-5600 p.s.i.g. with CO. Agitation causes an initial 200 to 400 p.s.i.g. pressure drop. The reaction mixture is then heated to 200°C . At 200°C . the pressure in the autoclave is approximately 9000 p.s.i.g., varying from about 8800 p.s.i.g. to 9400 p.s.i.g. H_2 is introduced into the vessel to increase the pressure 1000 p.s.i.g. During the first hour of reaction, a pressure drop of 1000 p.s.i.g. is observed; an additional 1000 p.s.i.g. H_2 is charged to restore the original pressure. H_2 is charged in this manner to the autoclave three times. The reaction time is 6 to 8 hours. The heat is then turned off and the reaction mixture is allowed to cool to room temperature with stirring.

When the reaction mixture has cooled to room temperature (40°C . or lower), the gases are vented and the stirring discontinued. The autoclave is unsealed. The reaction mixture is removed from the autoclave and added to one liter of water. The aqueous mixture is then placed into a distilling flask. The flask and contents are heated employing a heating mantle. At 76°C . $\text{Cr}(\text{CO})_6$ is observed to steam distill. Heating is continued for 1.5 hours to insure complete sublimation and steam distillation, at which time the aqueous mixture is cooled. The $\text{Cr}(\text{CO})_6$, after filtration, is washed with 50 ml. MeOH in three separate washings. The $\text{Cr}(\text{CO})_6$ is then washed with 50 ml. Et_2O to remove the MeOH. The $\text{Cr}(\text{CO})_6$ is removed from the Buchner funnel and placed in porcelain drying dish and air-dried $\frac{1}{2}$ hour. The yield of $\text{Cr}(\text{CO})_6$ is 37 g., 84% of theory.

Using the general procedure of the foregoing example, additional illustrative experiments are indexed comparatively as follows:

EXAMPLE 7

To illustrate recovery of iodine used in the practice of this invention, the steam distillation residue of Example 6 is oxidized by treatment with 100 ml. of concentrated HNO_3 and maintained at 98°C . for four hours. The weight of crude, wet I_2 sublimed is 88.0 g. Upon re-sublimation, 66.0 g. (87% recovery) of I_2 are obtained.

EXAMPLE 8

To illustrate recovery of acetonitrile, the original liquid portion of the steam distillate of Example 6 is redistilled. The $\text{CH}_3\text{CN}-\text{H}_2\text{O}$ azeotrope boils at $75^\circ-76^\circ \text{C}$. and weighs 280.0 g. A recovery of 60.5% acetonitrile is obtained.

While the specification thus far has referred to the use of chromic chloride as a reactant, the invention also contemplates the use of other chromium compounds such as chromic oxide (Cr_2O_3). When such a reactant is employed, hydrogen and/or another reducing agent is advantageous, e.g., up to 10 mols of Cr_2O_3 of carbon. Such a reaction is illustrated as follows:

EXAMPLE 9

A two-liter stirred autoclave is charged with 17.7 g. of a carbon-chromic oxide mixture¹ (0.1 mol of Cr_2O_3), 76 g. (0.3 mol) of iodine and 500 ml. of acetonitrile. After purging with CO, the vessel is charged to 5200 p.s.i.g. with CO. Stirring is begun and the reaction mixture is heated to 200°C . Hydrogen is then introduced in a series of four charges totaling 3000 p.s.i.g. over a period of six hours. Heating is discontinued. After cooling to room temperature the autoclave is vented and the contents added to one liter of water in a distilling flask. The flask is heated until the steam distillation of the $\text{Cr}(\text{CO})_6$ appears complete. The $\text{Cr}(\text{CO})_6$ so obtained is filtered, washed with 40 ml. of methanol and allowed to air dry for $\frac{1}{2}$ hour; it weighs 20.1 g. (45.6%).

EXAMPLE 10

The procedure of Example 6 is repeated using in four different experiments the following materials instead of acetonitrile: butyronitrile, propionitrile, succinonitrile and benzonitrile. In each case advantageous results are obtained.

EXAMPLE 11

A one-liter stirred autoclave is charged with 20.0 g. (0.05 mol) of tungsten hexachloride, 38.0 g. (0.15 mol) of iodine and 250 ml. of acetonitrile. After purging with CO, the vessel is charged to 3000 p.s.i.g. with CO and heated, with stirring, to 200°C . At this point the pressure is brought to 5000 p.s.i.g. by charging 600 p.s.i.g. of hydrogen. As the pressure drops it is returned to 5000 p.s.i.g. by addition of another 400 p.s.i.g. of hydrogen. After heating at 200°C . for five hours, the vessel is allowed to cool to room temperature, vented and opened. The contents are added to one liter of water in a distilling flask which is heated until steam distillation of the

¹ The indicated quantity of H_2 is gradually charged to reactor after reaction temperature increases to 200°C .
² 60.5% CH_3CN and 87.0% I_2 recovered.

$W(CO)_6$ appears complete. The white solid is collected on a filter, washed with three 10 ml. portions of methanol and allowed to air dry for one-half hour. This yields 14.6 g. (79%) of $W(CO)_6$, M.P. 172° C.

EXAMPLE 12

A one-liter stirred autoclave is charged with 27.3 g. (0.1 mol) of molybdenum pentachloride, 63.5 g. (0.25 mol) of iodine and 300 ml. of acetonitrile. After purging with CO, the reaction vessel is charged to 2800 p.s.i.g. with CO and heated, with stirring, to 200° C. At this point, 980 p.s.i.g. of hydrogen is introduced to raise the total pressure to 5000 p.s.i.g. As heating and stirring are continued, the pressure drops and an additional 720 p.s.i.g. of hydrogen is introduced to restore the pressure to 5000 p.s.i.g. After heating for five hours, the reaction vessel is allowed to cool to room temperature, vented and opened. The contents are added to one liter of water in a distilling flask which is heated until the steam distillation of the $Mo(CO)_6$ appears complete. The white solid is collected on a filter, washed with 30 ml. of methanol and allowed to air dry for one-half hour. The yield of $Mo(CO)_6$, M.P. 150° C. (dec.), is 17.8 g. (67%).

EXAMPLE 13

The general procedure of the foregoing examples is repeated except that CrI_2 is used as a source of chromium and iodine. There are combined in an autoclave equipped with an agitator and temperature control means 0.2 mol of CrI_2 in 500 ml. CH_3CN . The autoclave is pressurized with 5400 p.s.i.g. of CO @ 30° C. and heated to 200° C. whereupon 3600 p.s.i.g. of hydrogen is introduced. The reaction mixture is heated @ 200° C. with agitation for 6.5 hours. A 93% yield (41.5 g.) of $Cr(CO)_6$ is obtained via steam distillation of the reaction mixture.

EXAMPLE 14

The procedure of Example 1 is repeated using NaI as a source of iodine. There are combined in an autoclave 0.2 mol $CrCl_3$ and 0.6 mol NaI in 500 ml. of CH_3CN . The autoclave is pressurized with 5200 p.s.i.g. @ 25° C. and is then heated to 200° C. at which time 2300 p.s.i.g. of hydrogen is introduced. The reaction mixture is maintained at 200° C. for 6.5 hours. After steam distillation the yield of $Cr(CO)_6$ is 59% (26.0 g.).

EXAMPLE 15

The procedure of Example 11 is repeated using 0.1 mol of WCl_6 in 500 ml. of acetonitrile. Reaction is effected at 200° C. for 5.5 hours using an initial carbon monoxide pressure of 5700 p.s.i.g. at room temperature with 1500 p.s.i.g. carbon monoxide charged when the reaction temperature reaches 200° C., no hydrogen being introduced. A 59.5% yield of $W(CO)_6$ is obtained via steam distillation.

EXAMPLE 16

A two liter autoclave is charged with 10.4 g. (0.2 mol) finely-divided chromium metal (99% pure, 100 mesh), 76.0 g. (0.3 mol) iodine, and 500 ml. of acetonitrile. The autoclave is pressurized to 5300 p.s.i.g. with CO, and heated to 200° C. for 5 hours. During the 5 hour heating period, 3400 p.s.i.g. of H_2 is charged to the autoclave to maintain a pressure not less than 9600 p.s.i.g. and not greater than 10,000 p.s.i.g. After the vessel has cooled to room temperature, the reaction mixture is added to one liter of H_2O and heated. The $Cr(CO)_6$ steam distills and is separated from the liquid portion by filtration. After washing the $Cr(CO)_6$ with 30 ml. of MeOH and 30 ml. of ethyl ether, it is found to weight 34.1 g. (77% yield based on Cr metal).

EXAMPLE 17

The procedure of Example 3 is repeated using propio-

nitrile instead of acetonitrile. A 45% yield of $Cr(CO)_6$ is obtained.

It is to be understood that although the invention has been described with specific reference to particular embodiments thereof, it is not to be so limited, since changes and alterations therein may be made which are within the full intended scope of this invention as defined by the appended claims.

What is claimed is:

1. A process for preparing a carbonyl of a metal selected from the group consisting of chromium, tungsten and molybdenum which comprises introducing into a pressure reactor a metal source selected from the group consisting of the metal per se, trivalent chromium compounds, divalent chromium compounds, tungsten hexachloride, and molybdenum pentachloride; a substance selected from the group consisting of iodine and iodine containing compounds; and a nitrile of the formula $R(CN)_n$, wherein n is a number from 1 to 2, inclusive, and R is selected from the group consisting of lower alkyl, phenyl and lower alkylene; in the absence of any reducing metal; pressurizing the reactor with carbon monoxide to a pressure in the range of about 1000 to 10,000 p.s.i.g.; the ratios of reactants being at least 0.1 mole of iodine, 3 moles of nitrile and 6 moles of carbon monoxide per mole of metal source; heating the reactor to a temperature of about 150° to 325° C. and maintaining the temperature until the reaction is completed as evidenced by a pressure drop corresponding to the utilization of carbon monoxide; and separating the thus formed carbonyl of said selected metal by filtration and steam distillation.
2. The process of claim 1 wherein an amount of hydrogen is added which is sufficient to increase the pressure within the reactor about 2000 p.s.i.g. at 200° C., the weight ratio of hydrogen to carbon monoxide being no greater than 1:1.
3. The method according to claim 1 wherein the iodine is provided by using as the metal source an iodide of the metal.
4. The process according to claim 1 wherein the metal source is the metal per se.
5. The process according to claim 1 wherein the metal source is metallic chromium.
6. The method according to claim 1 wherein the metal source is chromium ore.
7. The process according to claim 1 wherein the metal source is a trivalent chromium compound.
8. The process according to claim 1 wherein the metal source is chromium trichloride.
9. The process according to claim 1 wherein the metal source is chromic oxide.
10. The process according to claim 1 wherein the metal source is a divalent chromium compound.
11. The process according to claim 1 wherein the metal source is the iodine-containing compound CrI_2 .
12. The process according to claim 1 wherein the metal source is metallic tungsten.
13. The process according to claim 1 wherein the metal source is tungsten hexachloride.
14. The process according to claim 1 wherein the metal source is metallic molybdenum.
15. The process according to claim 1 wherein the metal source is molybdenum pentachloride.
16. The process according to claim 1 wherein the nitrile is acetonitrile.
17. The process according to claim 1 wherein the nitrile is propionitrile.

UNITED STATES PATENT OFFICE
CERTIFICATE OF CORRECTION

Patent No. 3,100,687

August 13, 1963

John H. Wotiz

It is hereby certified that error appears in the above numbered patent requiring correction and that the said Letters Patent should read as corrected below.

Column 1, lines 39 and 40, strike out "in the absence of any reducing metal." and insert instead --. The expression "in the absence of any reducing metal" as employed in the specification and claims is intended as meaning that none of the commonly known reducing metals are added. This expression, however, is not intended to exclude the possibility of any of the reactants or materials present in the reaction performing the function of a reducing agent. --; column 2, line 57, for "i.g." read -- e.g. --; column 4, line 53, for "veseel" read -- vessel --; column 5, line 39, for "reepated" read -- repeated --; line 42, after "p.s.i.g." insert -- CO --.

Signed and sealed this 12th day of May 1964.
